UNITED STATES PATENT OFFICE.

THOMAS POTTERTON, OF LONDON, ENGLAND, ASSIGNOR TO ALBERT BELTON POTTERTON, OF SAME PLACE.

SAFETY-VALVE FOR BOILERS.

SPECIFICATION forming part of Letters Patent No. 569,670, dated October 20, 1896.

Application filed May 8, 1896. Serial No. 590,699. (No model.)

To all whom it may concern:

Be it known that I, THOMAS POTTERTON, a citizen of Great Britain, and a resident of London, in the county of Surrey, England, 5 have invented certain new and useful Improvements in Safety-Valves for Boilers, of which the following is a specification, reference being had to the accompanying drawings, forming a part thereof, in which similar 10 letters of reference indicate corresponding parts.

This invention relates to safety-valves for steam-boilers, water-boilers, and for general use in heating apparatus; and the object 15 thereof is to provide an improved device of this class which is simple in construction and operation and which is provided with a hollow spindle, with which is connected an escape valve or cock, by means of which the 20 water or steam can be drawn off when the cock is open, thus indicating the condition of the valve and whether it is in operative condition.

The invention is fully disclosed in the following specification, of which the accompanying drawings form a part, in which—

Figure 1 is a side elevation of my improved safety-valve; Fig. 2, a central vertical section thereof; Fig. 3, a side elevation of a modified 30 form of construction, and Fig. 4 a central vertical section thereof.

In the practice of my invention I provide a tubular head A, by which my improved valve may be connected with a boiler, hot-water 35 heater, or any similar device, and said tubular head is provided with an enlarged casing a, at the base of which is formed an annular chamber a², in the bottom of which are formed blow-holes a³, and said enlarged casing a is 40 provided with a cap B, which is mounted thereon and connected therewith by means of a screw-thread, and passing centrally through said cap is a hollow spindle D, the lower end of which is provided with a port or opening 45 d and an annular shoulder or flange d², below which is placed an annular cap d³, which is 50 adapted to hold in place an annular packing-ring d⁴, which may be composed of vulcanite or any preferred material, and which constitutes a valve which is adapted to be seated upon the upper end of the tubular

head a, as clearly shown in Fig. 2, and mounted on the hollow or tubular spindle D is a spiral spring E, one end of which bears upon the annular shoulder d² and the other upon the 55 cap B.

The cap B is provided with a valve-casing C, in which is placed a plug-valve G, and the valve-casing C is provided with a tubular connection H, which is preferably curved, as 60 shown, and through which water or steam may be discharged, and the cap B is provided with an annular flange or shoulder K, which is milled or otherwise roughened on the outer edge thereof, and which serves as means for 65 connecting the cap with the casing a or detaching the same therefrom.

In Figs. 3 and 4 I have shown a modified form of this construction, in which the hollow spindle D is provided at its upper end 70 with a three-way head L, to one side of which is secured the valve-casing C, with which is connected the pipe H, and the head L is provided at its upper side with an extension M, on which is mounted a plurality of weights 75 m, and the weights m serve, as will be understood, in place of the spiral spring E.

It will be understood that in both forms of construction the tubular spindle D is free to move through the cap B, and, whenever desirable, the valve G may be turned so as to admit of the discharge of water or steam, and when the valve is open if water escapes therefrom it will indicate that the valve-seating is free from incrustation or ice, and if water 85 does not issue through the valve it will indicate that something is wrong therewith, and said parts may be disconnected and examined.

This device is simple in construction and operation and perfectly adapted to accomplish the result for which it is intended, and I reserve the right to make all such changes therein and modifications thereof as fairly come within the scope of the invention.

Having fully described my invention, I 95 claim as new and desire to secure by Letters Patent—

1. The herein-described safety-valve which is provided with a vertically-movable hollow spindle, the upper end of which is provided 100 with a valve or cock, and a discharge-pipe, substantially as shown and described.

2. The herein-described safety-valve which is provided with a vertically-movable hollow spindle, the upper end of which is provided with a valve or cock, and a discharge-pipe, said hollow spindle being mounted in a casing at the lower end of which is a valve-seat, on which the lower end of the spindle is adapted to be seated, substantially as shown and described.

3. The herein-described safety-valve which is provided with a vertically-movable hollow spindle, the upper end of which is provided with a valve or cock, and a discharge-pipe, said hollow spindle being mounted in a casing at the lower end of which is a valve-seat,

on which the lower end of the spindle is adapted to be seated, and said spindle being also provided with a spring which is mounted thereon within said casing, and which is adapted to force the same upon the valve-seat, substantially as shown and described.

In testimony that I claim the foregoing as my invention I have signed my name, in presence of the subscribing witnesses, this 17th day of April, 1896.

THOMAS POTTERTON.

Witnesses:

THOMAS T. ROGERS,

ALFRED NUTTING.
